UNITED STATES PATENT OFFICE.

JOSEPH B. STRAUSS, OF CHICAGO, ILLINOIS.

BRIDGE.

1,157,450.

Specification of Letters Patent. Patented Oct. 19, 1915.

Application filed October 28, 1912. Serial No. 728,103.

To all whom it may concern:

Be it known that I, JOSEPH B. STRAUSS, a citizen of the United States, residing at Chicago, in the county of Cook and State 5 of Illinois, have invented a certain new and useful Improvement in Bridges, of which the following is a specification.

This invention relates to lifting devices such as lift bridges and the like, and has for 10 its object to provide a new and improved device of this description.

The invention is illustrated in the accompanying drawings, wherein—

Figure 1 is a side elevation diagrammatic 15 in form illustrating one form of invention as applied to a lift bridge; Fig. 2 is an end view of the device shown in Fig. 1; Fig. 3 is a side elevation showing the method of constructing the bridge without false work. 20 Fig. 4 is a sectional view of one of the tower members taken on line 4—4 of Fig. 1.

Like numerals refer to like parts throughout the several figures.

As illustrated in the drawing, there is 25 provided a vertically movable part 1, herein shown as a bridge span, and adapted to rest upon the piers 2, 3 and 4. At the end of the vertically movable part 1 is located a tower or support, preferably made of two 30 sections, one at each side, said vertically movable part projecting between the two separated sections. Associated with the sections of the tower are the racks 5, there being preferably four racks, two on each side 35 of the vertically movable part, the racks on one side being separated from the racks on the other side by the width of the span, the opposed separated racks being, however, preferably directly opposite each other. 40 Attached to the vertically movable part are the toothed wheels 6 which engage said racks. These toothed wheels are operatively connected with some suitable operating mechanism so that they can be rotated 45 so as to move the vertically movable part up or down along said tower. For purpose of illustration, I have shown a motor 7 connected with the vertically movable part, said motor driving a shaft 8 which is connected by beveled gears to shafts 9, which latter shafts by means of shaft 5^a and beveled gears 5^b operatively connect with the toothed wheels 6 so that when the motor is operated, all of said wheels will be rotated. 50 The tower supports or posts 9^a are preferably of I beam shape as shown in Fig. 4. The racks 5 are located within the channels. The vertically movable device 1 may be provided with wheels 6^a which engage one member 7^a of these beams (see Fig. 4). 60 The wheels 6^a are grooved so as to prevent longitudinal movement of the main span 1. The toothed wheels 6 are preferably pivotally connected at 6^b with the part 1 so as to give freedom of movement and prevent 65 binding. The pivots 6^b, it will be noted, (see Fig. 2) are shown as horizontal pivots. These pivots permit the main span a certain amount of movement without interfering with the connection between the pinions 70 6 and the racks 5. It will be noted that since the main span projects beyond the support and the arm is connected to it beyond the support, there will be a tendency, particularly at the starting and stopping, 75 for the main span to have a certain amount of movement, although said span is properly balanced, and these pivots permit this movement, as above set out. Connected with the vertically movable part in line 80 with the center of gravity is a connecting piece 10. Pivotedly connected with this connecting piece is an arm or lever 11 rotatably mounted upon the support or tower at the end of the vertically movable part. 85 There is also connected with this connecting piece 10, a link or lever 12, to which is connected a counterweight 13, the link 12 being connected with the lever 11. As herein shown, this connection is made through 90 the counterweight. It will be noted that the supports or main posts of the tower for the levers 11 which support the counterweights, each carries one of these levers and also carries a rack 5 and at the same time 95 forms a guide for the movable span. The lever 11 is also provided with a counterweight 14, the two counterweights counterbalancing the vertically movable part and the system of levers. By this construction, 100 means are provided for counteracting the circular movement of the ends of the lever 11, or link or lever 12, so that the vertically movable part can be lifted vertically. In other words, there are means provided for 105 compensating for the pivotal movement of the levers so as to allow the vertically movable part to be moved vertically without interference and without being moved longitudinally or through the arc of a circle, 110 the movement being confined to a vertical movement, as this is necessary to maintain 115

the proper connection between the toothed wheels 6 and the racks 5. It will be noted that the effect of the counterweights is applied to the span intermediate its ends which has the effect of reducing the dead load stresses of the span, thus securing economy by reducing the weight of metal required. In cases, for example, where the device is used in connection with a bridge 10 having a very long span, it may be desirable to shorten the levers 11 and 12. This may be done by providing the end of the span with a counterweight 15 so as to bring the center of gravity nearer the tower. The 15 position of the center of gravity may be therefore controlled at will to meet the conditions presented. If two towers and lifting mechanisms are provided, one at each side of the space to be spanned, they are 20 duplicates. It often happens, for example, that it is only possible to have an operating or lifting mechanism at one end of the main span. This is particularly true in cities where the land is exceedingly valuable and is taken up so that proper space 25 at each end of the span for a support cannot be secured. It also happens that in view of certain structures where bridges are used as in connection with elevated railroads and the like, it is not possible to provide space at both ends for the lifting apparatus. By means of the present device, these difficulties may be obviated, and in addition, a cheaper and more economical 30 construction may be provided due to the fact that only one lifting apparatus at one end of the span may be used. In the operation of the device, when it is desired to lift the part 1, the motor or other power device 35 is set into operation so as to rotate the toothed wheels in the direction to cause them to climb up the racks thus carrying the part 1 with them. Practically the entire weight of the part 1 is counterbalanced 40 by the counterweights 13 and 14, and hence the motor and pinions and racks have only a small amount of work to do. As the part 1 moves up, the counterweights move down and the system of levers compensate for the 45 pivotal movement of the levers so as to allow the part 1 to be moved vertically and secure the proper counterbalancing action at all its various positions.

This construction may be built on the 50 ground without false work. In building the device without false work, the tower portion is first constructed and then the levers 11 and 12 and connecting piece 10 may be connected. The end of the main span is 55 then built up to the connecting piece 10, the tower acting to support the apparatus and the end of the span. This built portion of the span is blocked in position by means of the blocks 16 and 17, so as to act 60 as a cantilever. When the span is built

out to the connecting piece 10, said connecting piece is attached thereto and then the remaining portion of the main span is built out in a cantilever form without the necessity of false work. The main span can 70 be built out in this manner while in its lifted position.

In this construction, a single tower or supporting device at one end of the main span may be built so as to satisfactorily 75 resist the lateral and horizontal forces on the span as said span is raised and lowered. By means of this construction, the bridge span may be lifted and lowered to a great height to permit vessels to pass thereunder, 80 and this may be done by the use of only a small amount of power.

I claim:

1. A bridge comprising a vertically movable span, operating mechanism at one end 85 of said span and operatively connected therewith at different points along its length and a counterbalancing device connected with said span at its center of gravity.

2. A bridge comprising a vertically movable span, a support located at one end of said span, operating mechanism connected with said span, at the support end thereof, at two points along its length, a counterbalancing arm connected to the span at its center of gravity said counterbalancing arm mounted upon said support. 95

3. A bridge comprising a vertically movable span, a fixed support at one end of said span, separated racks and coöperative 100 toothed wheels connected with said support and span respectively, means for actuating said toothed wheels so as to cause them to move along said racks and a counterweighted arm movably connected with the fixed 105 support said arm connected with said span at a point between its ends.

4. A bridge comprising a vertically movable span, a fixed support at one end of said span, separated racks and coöperative 110 toothed wheels connected with said support and span respectively, means for actuating said toothed wheels so as to cause them to move along said racks and a counterweighted arm movably connected with the fixed 115 support said arm connected with said span at a point between its ends and means associated with said arm for compensating for the pivotal movement thereof so as to allow the span to be moved vertically. 120

5. A bridge comprising a vertically movable span, a support located at one end of said span, operating mechanism connected with said span, at the support end thereof, at two points along its length, a counterbalancing arm connected to the span at its center of gravity said counterbalancing arm mounted upon said support and means for bringing the center of gravity of the span 125 nearer the end of the span where the opera- 130

tive mechanism is located than to the other end so as to shorten said counterbalancing arm.

6. A lifting device comprising a vertically movable part, a fixed support at one end of said vertically movable part, a counterweighted arm carried by said support and connected with the vertically movable part at its center of gravity and operating mechanism operatively connected with said vertically movable part at the end thereof where the support is located.

7. A lifting device comprising a vertically movable part, a tower at one end thereof having portions on opposite sides of said vertically movable part, one end of said vertically movable part extending between said portions, the other end projecting outwardly beyond the tower, two racks on each 20 of said portions located at different points along the length of said span, toothed wheels on the vertically movable part operatively engaging said racks, an actuating device for rotating the toothed wheels to cause them 25 to move along said racks, and means for counterbalancing said vertically movable part so that the two ends thereof move vertically when the toothed wheels are actuated.

8. A vertically movable bridge span in combination with means at one end thereof for restraining the vertical movement of said bridge span to substantially parallel lines, so that it occupies successive parallel positions when moved, said means comprising a support having two posts, one on each side of the roadway, racks on each of said posts, pinions on the span engaging said racks, a driving device for the pinions, an arm rotatively mounted on said support and 40 connected with said span intermediate its ends, a device associated with said arm for compensating for its rotative movement, and a counterweight connected with said arm.

9. A vertically movable bridge span in combination with means at one end thereof for restraining the vertical movement of said bridge span to substantially parallel lines, so that it occupies successive parallel positions when moved, said means comprising a 45 support having two posts, one on each side of the roadway, the end of said span projecting between said posts so that they limit the lateral movement thereof, an arm rotatively mounted upon each post, and connected with 50 said span at a distance from said posts, a device associated with each arm for compensating for its rotative movement, a counterweight connected with each arm, and opera-

tive mechanism for applying power to said span to lift and lower it. 60

10. A bridge comprising a vertically movable span, a support located at one end of said span, operating mechanism connected with said span at the support end thereof, a counterbalancing arm connected to the 65 span between its ends, said counterbalancing arm mounted upon said support.

11. A bridge comprising a vertically movable span, a single support therefor and means associated with said support for resisting the lateral and horizontal forces on the span as the span is raised and lowered. 70

12. The combination with the bridge span moving in parallel lines so that it occupies successive parallel positions, of a tower support at one end thereof having two front posts, one on each side of the roadway, between which the end of said span projects so as to be guided thereby, an arm rotatively mounted on each of said front posts, a device 80 associated with each arm for compensating for the rotative movement thereof, counterweights connected with said arms, racks also carried by said front posts, pinions on said span engaging said racks and driving mechanism for said pinions. 85

13. A bridge comprising a vertically movable span, an arm connected with said span, a support with which said arm is movably connected, an operating mechanism for said span comprising separated rigid racks, self-adjusting pinions engaging said racks, a shaft extending along the main span and connecting with said pinions so as to operate them and a motor connected with said shaft, 90 the operating mechanism and arm coöperating to lift the bridge. 95

14. A bridge comprising a vertically movable span, an arm connected with said span, a support with which said arm is movably connected, a counterweight connected with said arm, pinions connected with said main span at one end thereof at different points along its length, a shaft extending along the main span and operatively connected with 100 said pinions and a motor operatively connected with said shaft, the operating mechanism and arm coöperating to lift the bridge. 105

In testimony whereof, I affix my signature in the presence of two witnesses this 12th day of October 1912. 110
